UNITED STATES PATENT OFFICE

2,233,803

SELF-DUMPING WASHER

Jean Louis Boulade, Alturas, Calif.

Application February 28, 1939, Serial No. 258,912

4 Claims. (Cl. 68—210)

My invention relates to improvements in washers for use in commercial laundries and the like, and of the type disclosed in my United States Patent No. 2,046,607; dated July 7, 1936, and the 5 present improvements comprise improved and greatly simplified means for automatically operating the dumping of the washer by means of a single control, operating in conjunction with simple and improved fluid pressure actuated 10 means for completely carrying out in proper sequence the several steps required to discharge or dump the washer, after a washing operation has been completed.

The primary object of the present invention is 15 to provide a new and improved self-dumping washer.

Another object is to provide a new and improved self-dumping washer having improved means by which the several steps in dumping and 20 returning to a normal loading or washing position may easily be carried out automatically in proper sequence and with a saving of time and labor.

A further object is to provide a new and improved self-dumping washer that may be easily 25 unloaded by practically untrained or nontechnical operatives.

A still further object is to provide a new and 30 improved self-dumping washer having improved and greatly simplified means for operating the same.

I accomplish these and other objects by means 35 of the improved device disclosed in the drawings forming a part of the present application, and in which—

Fig. 1 is a longitudinal sectional view taken on line 1—1 of Fig. 5 of the drawings, in the direction indicated;

Fig. 2 is a plan view, partly in section, of the 40 device with the cover of the housing removed;

Figs. 3 and 4 are enlarged broken detailed views of the locking mechanism;

Fig. 5 is an end elevation, with a portion of the 45 operating mechanism shown in vertical section;

Fig. 6 is a detailed sectional view of one of the controlling valves;

Fig. 7 is a transverse sectional view taken on 50 line 7—7 of Fig. 1, in the direction indicated;

Fig. 8 is a transverse sectional view taken on line 8—8 of Fig. 1, in the direction indicated;

Figs. 9, 10, 11 and 12 are enlarged broken and 55 vertical sectional view of the operating and release mechanism;

Figs. 13 and 14 are enlarged sectional views dis-

closing the mechanism for holding the cylinder closed; and

Fig. 15 is an enlarged, broken sectional view of the mechanism for moving the washer to dumping position.

Referring to the drawings:

The numeral 1 is used to designate a suitable housing containing a suitable tank or vat 2 within which is contained the usual cleansing solution of soap and hot water or other detergent 3. 10 The housing 1 is provided with a preferably semi-cylindrical cover or lid 4 hingedly connected thereto and rigidly connected to a pintle 6 extending beyond one end of the housing 1 and provided with a gear 7 extending through a slot 15 8 in the side of a cylinder 9 and meshing with the teeth 11 of a piston 12 slidably mounted within said cylinder 9, said top or lid 4, gear 7, cylinder 9 and piston 12 being hereinafter referred to as the first fluid pressure actuated means, the purpose of which will hereinafter more fully appear.

An open rectangular cradle 14 is rotatably mounted within the housing 1 by means of trunnions 16, one of which extends exteriorly of the housing 1 and is provided with a suitable 25 sheave or pulley 17, by means of which said cradle may be rotated.

A cylindrical washer 18 is split longitudinally to provide an upper half 19 and a lower half 21, said upper half 19 being hingedly connected at 30 one longitudinal edge as at 22 to one side of the cradle 14 and provided at its opposite edge with an arcuate flange 23 normally resting upon a tubular pintle 24, by means of which pintle 24 said lower half 21 is hingedly connected to the opposite side of said cradle 14. The edge of the lower half 21 opposite its pintle 24 is provided with a series of arcuate extensions 26 which pass through openings 27 in the hinged edge of the upper half 19 and rest upon its pintle 22, as disclosed in Figs. 2, 7, 13, and 14 of the drawings, to support said lower half 21 when closed or normal to hold that edge locked in conjunction with the upper half 19 while the washer 18 is rotating. The upper half 19, when closed, and when the 40 cradle 14 is reversed in rotating and said upper half is lowermost, engages and prevents said arcuate extensions 26 from being swung away from said cradle 14 and pintle 22 and thereby locks the free edge of the lower half to said 45 cradle 14 and upper half 19. When the upper half 19 is moved to uncover the lower half 21, these extensions 26 are also uncovered and that edge of said lower half 21 is free to move to dumping position, hereinafter more fully set forth 50 55

and as disclosed in detail in Fig. 14 of the drawings.

The arcuate flange 23 of the upper half 19 of the washer 18 is provided with a locking device 5 comprising a plurality of headed pins 27 which pass through apertures 28 in the tubular pintle 24 of the lower half 21 and also through similar apertures 29, within a tube 31 slidably mounted throughout the length of the tubular pintle 24, 10 and registering with the apertures 28 when the several parts are moved to unlocking position, hereinafter more fully set forth.

The apertures 29 of the tube 31 are provided with reduced slots or extensions 32 of sufficient 15 dimension to engage the shanks of the headed pins 27 but insufficient to permit the passage of the heads thereof therethrough. The said tube 31 is normally and yieldingly held in locking position, as disclosed in Figs. 1, 2, and 3 of the 20 drawings, by means of a spring 35 interposed between a transverse pin 33 rigidly set in the tubular pintle 24, which passes through longitudinal slots 34 in said tube 31 to permit longitudinal movement only of said tube 31 within 25 said pintle 24, and a second transverse rigid pin 36 set within said tube 31, thereby normally holding the apertures 29 out of register with the apertures 28 of the pintle 24, and the slots or 30 extensions 32 in engaging relation with said pins 27.

One end of the pintle 24 extends exteriorly of one end of the cradle 14 and is provided with a nut head 37, through the center of which is slidably mounted one end of the tube 31, as disclosed in detail in Fig. 15 of the drawings, the end of said tube 31 being normally and yieldingly held flush with the outer face or end of the head 37 by the tension of the spring 35 and the limiting stop as provided by the action of the pin 33 within the slot 34.

A dumping mechanism comprises the following:

A square shaft 38 is slidably mounted for limited longitudinal movement only within the hub 39 of a gear 41 rotatably and coaxially mounted 45 within the housing 1 and in respect to the tubular pintle 24 and tube 31 therein. The gear 41 extends through a slot 42 within a second cylinder 43 and engages the teeth 44 on a piston 50 46, slidably mounted within said cylinder 43, which mechanism, from the square shaft 38 to the piston 46 is hereinafter referred to as a 55 separate fluid pressure actuated means, as will more fully appear.

The square shaft 38, aligned coaxially with the nut head 37, has rigidly mounted upon its adjacent end a socket head 47 into which socket head 47 the end of the square shaft 38 extends sufficiently to engage the end of and move the tube 31 slidably mounted within said nut or head 37 and the tubular pintle 24 of which said head 37 is a rigid part, when said socket head 47 is moved to engage the nut head 37, and move the opposite end of said tube 31 beyond the 60 opposite end of the cradle 14 and into a bearing 49 arranged coaxially with said tube 31, when the cradle 14 is in dumping position, to provide an additional support for said cradle and lower half 21, when said lower half is being moved to 65 dumping position.

A suitable spring 51 is interposed between the hub 39 of the gear 41 and a collar 52 on said shaft and normally and yieldingly holds the shaft 38 and socket head 47 thereon from engaging the nut head 37. Engagement of said

socket head 47 with the nut head 37 is also prevented, while the washer or cylinder 18 is rotating during a washing process, until said cylinder comes to rest in unloading or dumping position, when said heads 37 and 47 are coaxially aligned, by means of a circular guard rail 53 mounted upon the end of the cradle 14 and arranged in the same plane or flush with the outer face or surface of the nut head 37 and having the ends of said circular guard 55 offset 10 back of said plane only a short distance on each side of said nut head 37, to permit engagement of the socket 47 with the nut head 37 only when coaxially aligned with the lower half 21 in a dumping position, as disclosed in details in Fig. 15 of the drawings.

The square shaft 38 is provided, at the end opposite the head 47, with a rounded portion 53 rotatably and slidably extending into a cylinder 54 provided with a round port 56 to a 20 first connection 57 leading to the cylinder 9 of the first fluid pressure actuated means, and an elongated port 58, in the same transverse plane with the port 56, leading to a second connection 59 leading into the bottom of the cylinder 43, 25 of the separate fluid pressure actuated means.

A sleeve valve 61 is rigidly connected to the rounded end 53 of the square shaft 38 and is rotatably and slidably mounted within the cylinder 54, said sleeve being normally held by the 30 tension of the spring 51 over said ports 56 and 58. The sleeve 61 is also provided with a round port 62 normally in longitudinal alignment with the first port 56. A passage 63 connects the interior of the cylinder 54 and the inside of the sleeve 35 61 with a three way cock 64 which, by means of a lever 65 may be partially rotated to connect said passage 63 with a source of fluid pressure 66 or with a release or exhaust port 67.

A cam 69 is connected to the cock 64 and is 40 provided with stops 71 and 72, preferably beveled on one side, arranged to be engaged by a pin 73 adjacent one end of a flexible bar 74 slidably mounted for longitudinal movement through a bracket 76 supporting the cylinder 54, 45 the other end of said flexible bar 74 being operatively connected to one arm of the bellcrank 77 pivotally mounted upon and supported by the cylinder 54, the other arm of said crank 77 lying within the path of and, as hereinafter 50 more fully set forth, operated by the spokes of the gear 41.

One end of a shunt connection 81 connects with the interior of the cylinder 9 only when the piston 46 therein is moved to its uppermost 55 position to open the cover 4, hereinafter explained, the other end of said connection 81 being connected to the enlarged bottom 82 of the cylinder 43 within which enlarged portion 82 is slidably mounted a balanced valve 84 normally urged to follow the piston 46 when its starts to move upwardly by means of a spring 85 and to engage a seat 86 and close said other end of the shunt connection 81 to said cylinder 43.

A pair of latches 91 are freely suspended from 65 the top interior of the cover 4 of the housing 1 and have their lower free ends resting within inclined pockets 93 of the lower part of the said housing 1 to prevent said latches from engaging catches 92 on the upper half 19 of the washer 18, 70 when said cover 4 is closed. When the cover 4 is raised the free ends of said latches 91 swing clear of said pockets 93 and, actuated by the attraction of gravity, engage said catches 92 and raise said upper half 19 with said cover 4.

Preferably, the diameter of the valve 61 is greater than the diameter of the piston 12 of the first fluid pressure actuated means, and the diameter of the piston 46 of the separate fluid pressure actuated means is less than the diameter of the piston 12.

In operation:

When the washer 18 is ready for dumping, the power, not shown, for rotating said washer and the cradle 14 is shut off and as the speed of rotation of said cradle decreases sufficiently, the lever 65 is moved to set the cock 64 in the position to connect the source of fluid pressure 66 with the passage 63 which will first move the sleeve valve 61 and shafts 53 and 38 to in turn move the outer face of the socket head 47 against the face of the guard rail 55. When the nut head 37 becomes aligned with the socket head 47, and the speed of rotation of the cradle 14 decreases sufficiently to permit engagement, the socket head 47 will enter the offset portions of the guard 55 and the said nut head 37 will be engaged by said socket head 47 and the protruding head of the square shaft 38 will engage the adjacent end of the tube 31 and move the same to disengage the headed pins 27 and move the opposite end of said tube 31 into the bearing 49, thereby securing the cradle 14 and washer 18 against rotation. The three way cock will then be connected to the source of fluid pressure and in the position indicated in Fig. 9 of the drawings, with the stop 72 against the pin 73 of the flexible rod 74.

As the fluid pressure moves the sleeve valve 61 to accomplish the above, the aperture 62 in said sleeve 61 will uncover the port 56 to the first connection 57 and said fluid pressure is passed into the cylinder 9, moving the piston 12 upwardly and rotating the gear 7 to raise the cover 4 of the housing 1. In the initial portion of such movement the latches 91 will be cleared from their retentive pockets 93 and will engage the catches 92 of the upper half 19 and raise the same to the open position indicated in dotted lines at the left of Fig. 7.

When the cover 4 and upper half 19 are opened, the piston 12 will be in its uppermost position and the bottom of said piston 12 will uncover the shunt connection 81 to the lower end of the cylinder 43 and start raising the piston 46 therein. As piston 46 continues its upward movement and rotates the gear 41, first, the balanced valve 84 will follow and close the shunt connection 81, to the cylinder 43, thereby holding the cylinder 9 under compression to lock the cover 4 and upper half 19 in raised position, and the square shaft 38, rotated during movement of the lower half to dumping position, will in turn rotate the sleeve valve 61 and close the port 56, thereby further closing said cylinder 9 against release. Continuing, the sleeve valve 61 will uncover the elongated port 58 and admit the fluid pressure to the second connection 59 and thereby continue to raise the piston 46 and move the lower half 21 to full dumping position.

At this time the formerly lower spoke of the gear 41 moving to the former position of the upper spoke, as disclosed in Fig. 5 of the drawings, will engage the bell-crank 77 and gradually move the flexible bar 74 and pin 73 thereon to engage the lug or stop 72, as disclosed in Fig. 9 of the drawings, and move the cam 69 and cock 64 to neutral position, as disclosed in Fig. 10 of the drawings, so that the supply of fluid pressure to the cylinder 43 will gradually be discontinued and movement of said piston 46 and lower half 21 will

be automatically stopped, and said upper half will be held in open position and the lower half 21 will be held in dumping position until the cock 64 is again operated.

After the lower half is unloaded, by moving the lever 65 to releasing position, as disclosed in Fig. 11 of the drawings, the stop 72 will contact the pin 73 on the flexible bar 74 and pressure will be released from the cylinder 43 through the second connection 59, elongated port 58 and release port 67 of the cock 64 until the lower half is returned or lowered to normal position in the cradle 14 and the upper spoke of the gear 41 gradually reverses the bell-crank 77 and moves the rod 74 and pin 73 thereon to shove the cam 69 and cock 64 to neutral position, as disclosed in Fig. 12 of the drawings. The upper half 19 will still be locked against descent.

When the lower half 21 is again charged or loaded, the bar 74 is flexed or bent, as disclosed in dotted lines in Figs. 1 and 9 of the drawings, and the cock 64 is again moved to releasing position to permit the escape of fluid pressure from the cylinder 9 to lower the cover 4 and upper half 19, the balanced valve 84 having been moved by the descent of the piston 46 and the release port 56 having been opened by the return of the lower half to lowered position.

As the lower half 21 drops to lowered position the fluid pressure is released from both cylinders 9 and 43 and finally the tension of the spring 51 will move the sleeve valve 61 to release or disengage the socket head 47 from the nut head 37 and permit the tube 31 to be moved by the tension of the spring 35 to engage the headed pins 27 and lock the upper and lower halves together and to release said tube 31 from the bearing 49, so that the washer 18 is again ready for rotation.

Having described my invention I claim:

1. A self-dumping washer comprising a housing; a cover hingedly mounted on said housing; a cradle mounted for horizontal rotation within said housing; a cylindrical washer in said cradle and split longitudinally to provide upper and lower halves, each half being hingedly connected to an opposite side of said cradle; a cylinder; a piston slidably mounted within said cylinder; means operatively connecting said piston with the cover of said housing to open and close the cover when said piston is actuated; means secured to and actuated by opening of said cover to engage and open said upper half of said washer; a second cylinder; a second piston slidably mounted within said second cylinder; dumping means connected to said second piston for engaging and dumping said lower half of said washer and normally disengaging said lower half; a source of fluid pressure; connections from said source to said first and second cylinders; means for moving said dumping means into engagement with said lower half; and fluid pressure controlling means connected to said connections to first actuate said first piston to raise said cover and upper half and then to actuate said second piston to move said lower half to dumping position.

2. A self-dumping washer comprising a housing; a cover hingedly mounted on said housing; a cradle mounted for horizontal rotation within said housing; a cylindrical washer mounted in said cradle and split longitudinally to provide upper and lower halves, each half being hingedly connected to an opposite side of said cradle; a cylinder; a piston slidably mounted within said cylinder; means operatively connecting said piston with the cover of said housing to open and

close the same when said piston is actuated; means secured to and actuated by the opening of said cover to engage and open said upper half when said cover is opened; a second cylinder; a second piston slidably mounted within said second cylinder; dumping means operatively connected to said second piston for engaging and dumping said lower half and normally disengaging said lower half; means for moving said dumping means to engage said lower half; a source of fluid pressure; connections from said source to said first and second cylinders; and fluid-pressure controlling means connected to said connections to first actuate said first piston to open said cover and upper half and thereafter to actuate said second piston to move said dumping means and said lower half to dumping position, and for holding said cover and upper half in open position while said lower half is moved to dumping position and returned to normal position within said cradle.

3. A self-dumping washer comprising a housing; a cover hingedly mounted on said housing; a cradle mounted for horizontal rotation within said housing; a cylindrical washer mounted within said cradle and split longitudinally to provide upper and lower halves, each half being hingedly connected to an opposite side of said cradle; a cylinder; a piston slidably mounted within said cylinder; means operatively connecting said piston with the cover of said housing to open and close the same when said piston is actuated; means actuated by the opening of said cover to engage and open said upper half; a second cylinder; a piston slidably mounted within said second cylinder; dumping means connected to said second piston for engaging and dumping said lower half and normally disengaging said lower half; a third cylinder; a sleeve valve slidably mounted within said third cylinder and connected to said dumping means; a source of fluid pressure connected to said third cylinder; a normally closed connection from said third to said first cylinder; a second normally closed connection from said first cylinder to said second cylinder; and fluid-pressure controlling means connected to said third cylinder for admitting fluid pressure thereto to move said sleeve valve to move said dumping

mechanism into engagement with said lower half and to open said connection from said third cylinder to said first cylinder to move said first piston to open the cover of said housing and open said upper half and to open said second connection from said first cylinder to said second cylinder to operate said dumping means.

4. A self-dumping washer comprising a housing; a cover hingedly connected to said housing; a cradle mounted for horizontal rotation within said housing; a cylindrical washer mounted in said cradle and split longitudinally to provide upper and lower halves, each half being hingedly connected at one edge to an opposite side of said cradle; a cylinder; a piston slidably mounted within said cylinder; means operatively connecting said piston to said cover to open and close the said cover when said piston is actuated; means secured to and actuated by the opening of said cover to engage and open said upper half; a second cylinder of smaller diameter than the diameter of the first cylinder; a piston slidably mounted within said second cylinder; dumping means connected to said second piston for engaging said lower half when in lowermost position and for dumping the same, said dumping means being normally disengaged from said lower half; a third cylinder of larger diameter than the diameter of the first cylinder; a sleeve valve slidably mounted within said third cylinder and connected to said dumping means; a source of fluid pressure connected to said third cylinder; a fluid-pressure connection from said third cylinder to said first cylinder and normally closed by said sleeve valve; a second fluid-pressure connection from said first cylinder to said second cylinder and normally closed by said first piston when said cover and upper half are closed; and fluid-pressure controlling means for admitting and controlling fluid-pressure first to said third cylinder to first move said sleeve to move said dumping means into engaging relation with said lower half, then uncover the connection to the first cylinder to actuate the piston therein to open said cover and upper half and then uncover said second connection to said second cylinder to actuate said dumping means.

JEAN LOUIS BOULADE.
